UNITED STATES PATENT OFFICE.

CLARENCE W. LASKAY, OF NEW YORK, N. Y.

TWO-CYCLE MARINE ENGINE.

1,001,866.

Specification of Letters Patent. Patented Aug. 29, 1911.

Application filed November 16, 1907. Serial No. 402,383.

To all whom it may concern:

Be it known that I, CLARENCE W. LASKAY, a citizen of the United States, residing in the borough of Manhattan, city, county, and State of New York, have invented certain new and useful Improvements in Two-Cycle Marine Engines, of which the following is a specification, reference being had therein to the accompanying drawings.

10 Figure 1 is a longitudinal vertical sectional view taken on the line I—I of Fig. 2; Fig. 2 a similar view on line II—II of Fig. 1; and Fig. 3 a transverse vertical sectional view on the line III—III of Fig. 2.

15 One of the main objects of this invention is to provide means for taking the mixture from the carburetor into the crank case through a port controlled by a rotating cylindrical valve, said valve being provided 20 with a slot which is adapted to register with the intake port during the rotation of the crank shaft. This cylindrical valve is, of course, mounted in such a position that its slot will register with the intake port during 25 the compression stroke of the piston.

Another object of the invention is to provide means whereby the engine may be reversed, one valve controlling the intake of mixture whether the engine be running forward or reversed.

Other important objects and advantages of the invention resulting from the construction and arrangement of my valve will appear hereinafter.

35 Referring to the various parts by numerals, 1 designates the engine cylinder; 2 the spark plug; 3 the piston within the cylinder; 4 the pitman; 5 the crank and 6 the crank shaft. The engine as shown is of the 40 two-cycle type and is provided with the exhaust port 7, and the intake port 8 leading into the crank case. The crank case is cylindrical, a portion of it forming a cylindrical valve seat for the valve said valve 45 seat being formed on a circle struck from the center of the crank shaft. Mounted on the crank shaft within the crank case is a broad-faced cylindrical valve 9 which is preferably equal in diameter to the interior 50 of the crank case and fits snugly within the valve seat formed in the same, in such a position as to close the intake port. This valve consists of the rim 10 and the supporting spokes 11. To permit the mixture to flow 55 through the intake port into the crank case the valve 9 is formed with a slot 12 in its

periphery or face, said slot extending around slightly less than one-half the periphery of the valve. I preferably form it the width of the intake port less than one-half the circumference of the valve, for the purpose which will hereinafter appear. The interior of the hub of the cylindrical valve is slightly greater in diameter than the diameter of the crank shaft so that there will be a slight space between said parts, the shaft being capable of a slight vertical movement independently of the valve. The purpose of this is to permit the shaft to settle in its bearings, as the bearings become worn, without affecting the fit of the valve against its valve seat. It will be readily understood that while there will be practically no wear between the valve and its seat there is considerable wear between the crank shaft and its bearings, and unless the shaft be permitted to settle in its bearings without moving the valve from its seat the valve would soon leak. The crank shaft is provided with a key 13 which fits in a key-way 14 formed in the hub of the valve, the key being of sufficient size to permit of the independent movement of the shaft just referred to without disconnecting the key from the key-way.

To permit the engine to be reversed and at the same time adapt the cylindrical valve for use as an intake valve during the reversed action of the engine, the key-way is in the form of a slot or recess extending one-half way around the hub, thereby providing two end-walls 15 and 16 against which the key will bear when the engine is running. When it is running forward the key will bear against the wall 15 of the key slot; and when the engine is reversed, the key will move around through the slot without moving the valve until it engages the wall 16. This free one-half turn of the shaft will so change the relations of the piston and the valve that the valve will act as an intake valve for the reversed condition of the engine. This will be readily understood by reference to Figs. 1 and 3 of the drawing in which the engine has completed its compression stroke, the intake valve having been just closed.

Should it be desired to reverse the engine (supposing the engine to have stopped in the position shown in Figs. 1 and 3) it will be necessary to turn the crank shaft in the reverse direction one-half a revolution. This will bring the piston to its lowermost

position and the key into engagement with the wall 16 of the key-way in the valve. A continued rotation of the crank shaft in the reversed direction will open the intake port 5 and permit the piston to draw mixture into the crank case. It will, therefore, be seen that the valve will act equally well in the forward or reversed action of the engine.

10 It will be readily understood that the partially compressed mixture from the crank case will pass upward into the engine cylinder through port 17 when the piston is at the end of its working stroke. It will also 15 be understood that the burned gases from the engine cylinder will escape through the exhaust port 7 slightly before the port 17 is opened.

By the means herein described I secure an 20 intake of mixture during the entire compression stroke of the piston so that whether the engine be working at a high speed or a low speed an adequate supply of mixture will be drawn into the crank case. This is 25 of great importance for the reason that with the two cycle engines of the ordinary construction, where the intake of the mixture from the carburetor is near the end of the compression stroke, it is impossible to get a 30 proper supply of mixture at a low speed. The result is that the engine cannot be run at a low speed. It is further true that when running at a high speed the ordinary engine 35 which takes mixture at the end of its compression stroke, by reason of the vacuum caused in the crank case, takes in too great a supply of free gasoline vapor, said vapor not having had time to be thoroughly mingled with the proper amount of air to make a 40 good mixture.

By providing means whereby mixture is drawn into the crank case during practically the entire compression stroke of the piston the speed of the engine may be nicely 45 controlled by controlling the supply of mixture.

By employing a cylindrical valve such as shown the engine is particularly well adapted for use in marine work for the reason 50 that when the engine is reversed the shaft may have a slight end-wise movement because of the change in thrust strain without in the least affecting the accurate fit of the cylindrical valve to its seat, and without 55 causing any leak around the valve. This is of great importance. It will, therefore, be seen that I not only permit the crank shaft to settle in its bearings as the bearings wear, without disturbing the fit of the valve, but I 60 also provide for taking up the thrust on the shaft without in the least affecting the efficiency of the valve. These are important

points and contribute considerably to the efficiency of the engine.

It will also be noted that I provide a mechanically operated valve which serves to control the intake of mixture to the crank case during both the forward and reversed action of the engine, the valve being automatically adjusted to its work by the simple reversed action of the crank shaft.

Having thus described my invention, what I claim as new and desire to secure by Letters Patent, is:—

1. A two-cycle engine comprising a closed 75 crank casing formed with a mixture inlet port, a crank shaft, a cylindrical valve within the casing and loosely mounted on the crank shaft, said valve having a port adapted to register with the inlet port in the 80 crank casing, a key secured to the crank shaft, the valve being formed with a key-way or slot to receive said key and extending substantially one-half way around the valve, whereby the shaft may have a one- 85 half revolution independently of the valve.

2. A two-cycle engine comprising a cylinder, a closed crank casing connected thereto and formed with an interior curved valve seat, an inlet port being formed through 90 said valve seat, a crank shaft mounted in said casing, the valve seat being on a curve struck from the center of said shaft, a hollow cylindrical valve carried by said shaft and working on the valve seat, said valve 95 being formed with a port adapted to register with the port in the valve seat, the solid portion of the valve serving to close the inlet port in said seat, the valve seat being broader than the cylindrical valve, whereby 100 said valve may have a slight axial movement without disturbing the working relation of the inlet ports.

3. A two-cycle engine comprising a cylinder, a closed crank casing provided with 105 an interior valve seat having an inlet port therethrough, a crank shaft extending through the crank casing concentric with the valve seat, a cylindrical valve loosely mounted on the shaft and working on the 110 valve seat, said valve being formed with a port adapted to register with the inlet port, and means for loosely connecting said valve to the shaft to permit said shaft to have a one-half revolution independently of the 115 valve.

In testimony whereof I hereunto affix my signature in the presence of two witnesses this 14th day of November 1907.

CLARENCE W. LASKAY.
